(57) **CLAIM**

We claim the ornamental design for digital video disc recorder with hard disk recorder, as shown.

DESCRIPTION

FIG. 1 is a front, top and right side perspective view of digital video disc recorder with hard disk recorder showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view thereof with the power turned on, the door open and the tray drawn out.
